(57) **CLAIM**

The ornamental design for inhaler, as shown and described.

DESCRIPTION

FIG. 1 is a front view of an inhaler showing our new design;

FIG. 2 is rear view thereof;

FIG. 3 is a right view thereof;

FIG. 4 is a left view thereof;

FIG. 5 is bottom view thereof;

FIG. 6 is a top view thereof; and,

FIG. 7 is a top perspective view thereof.

The broken lines in the drawings depict portions of the inhaler that form no part of the claimed design.

1 Claim, 7 Drawing Sheets
